[57] CLAIM

The ornamental design for a paint container holder, as shown and described.

DESCRIPTION

FIG. 1 sets forth a perspective view of a paint container holder showing the present invention new design; FIG. 2 is a top plan view thereof; FIG. 3 is a bottom plan view thereof; FIG. 4 is a left side view thereof; FIG. 5 is a right side view thereof; FIG. 6 is a front view thereof; and, FIG. 7 is a rear view thereof.

The broken line showing of a ladder and a container is for illustrative purposes only and forms no part of the claimed design.
